UNITED STATES PATENT OFFICE

120,247

DESIGN FOR A PIN CLIP OR SIMILAR ARTICLE

Dominick Saltarelli, Chicago, Ill.

Application March 11, 1940, Serial No. 90,821

Term of patent 3½ years

To all whom it may concern:

Be it known that I, Dominick Saltarelli, a citizen of the United States of America, residing at 320 South Franklin Street, Chicago, Illinois, have invented a new, original, and ornamental Design for a Pin Clip or Similar Article, of which the following is a specification, reference being had to the accompanying drawing, forming a part thereof.

Fig. 1 is a front view of a pin clip showing my new design and Fig. 2 is a side view of the same.

I claim:

The ornamental design for a pin clip or similar article, substantially as shown.

DOMINICK SALTARELLI.
